UNITED STATES PATENT OFFICE.

JANE KILLIAN McAFFEE, OF BROOKLYN, NEW YORK.

CLOTHES-RACK.

1,215,175.

Specification of Letters Patent.

Patented Feb. 6, 1917.

Application filed August 8, 1916. Serial No. 113,771.

To all whom it may concern:

Be it known that I, JANE KILLIAN McAFFEE, a citizen of the United States, residing in the borough of Brooklyn, county of 5 Kings, city and State of New York, have invented certain new and useful Improvements in Clothes-Racks, of which the following is a specification, reference being had therein to the accompanying drawings.

10 The invention relates to an improvement in extensible clothes racks for use in apartments where there are restrictions against the use of poles and pulley lines or where the only place for drying clothes is the roof 15 and the number of families desiring to use it is such that each one's use is very much restricted or where there are very young children and the mother can not leave them alone to go to the roof.

20 The principal object of the invention is to provide a rack of this character which can be secured in the lower portion of a window and which when in use will extend outward and upward and which when not in 25 use can be folded into a small compass and not be unsightly.

A further object of the invention is to 30 provide a rack of this character in which each of the hanging members will have a four inch clearance of those beneath it which has been ascertained to be the clearance necessary for suitably drying clothes.

35 A further object of the invention is to provide a rack of this character which can be loaded conveniently by a woman without leaning out of the window or straining at a pulley rope and which can be extended when loaded by mechanical means operated from inside the room and which can be securely held in its extended position and when it is desired to take the clothes in their own weight will assist in the operation.

40 A further object of the invention is to provide a rack of this character which is adjustable to different widths of windows so that it can be fitted to a window without difficulty by an unskilled person with ordinary hand tools.

45 Other objects of the invention will be apparent from the detailed description thereof hereinafter made when read in connection with the accompanying drawings forming a part hereof wherein a preferable form of the invention is shown and wherein like numerals of reference refer to similar parts in 50 the several views.

While a preferred form of the invention is illustrated in the accompanying drawings it will be understood that various changes and alterations can be made in the arrangement, positioning and construction of the several parts without departing from the spirit of the invention.

Generally the invention consists of suitable supporting members adapted to be secured to the inside of the sides of the window frame in the lower portion thereof, a rack of the lazy tongs type carried by the supporting members at a suitable angle so that when in use the rack will extend outward and upward and give each of the rods connecting the lazy tongs sides a clearance of four inches, rods adapted to telescope connecting the lazy tongs sides and jointed arms at the sides and lower portion of the inner end of the rack adapted to extend the rack and hold it in the extended position and when folded to close the rack.

In the accompanying drawings, Figure 1 is a side elevation of a rack embodying the invention shown in place in a window, the full lines showing the rack in an extended position and the dotted lines in a closed position, the adjacent parts of the window frame being broken away; Fig. 2 is a top plan of the rack in an extended position; Fig. 3 is a detail view of one of the rods connecting the sides of the rack partly broken away to show the telescopic connection and stop; Figs. 4 and 5 are detail side and top plan views showing the locking device; Figs. 6 and 7 are detail side and top plan views of a modified form of securing the supporting members to the sides of the window frame; Fig. 8 is a side elevation of one of the supporting members pivotally secured to the sides of the window frame with adjacent parts in section or broken away the better to show the connection; Figs. 11 and 12 are detail views of elements of the pivotal connection; Fig. 9 is a side elevation partly in section and with adjacent parts broken away showing the rack secured to the top of a receptacle resting on the window sill with the top in a vertical position; and Fig. 10 is a front view partly in section and with parts broken away showing receptacle with top in a vertical position.

Referring to the accompanying drawings, two supporting members 1 are provided which may be attached in any suitable manner, as by screws 2, to the insides of the

sides of the window frame 3 near the lower portion thereof.

The rack consists of a series of parallel bars 4 and 5 on each side which are pivotally connected at their extremities 6 and 7 and at their centers 8 and 9 by rods 11. One of the parallel bars 4 on each side of the rack is secured in any suitable manner, as by screws 10, to the corresponding supporting member 1 at such an angle that when the rack is extended each of the rods 11 connecting the bars 4 and 5 will have a clearance of four inches.

The rods 11 are telescopic and are secured in the bars 4 and 5 in any suitable manner, as by having their ends 12 which pass through the bars 4 and 5 reduced in size to form shoulders which abut against the inner side of the bars 5 and by cotter pins 14 passing through the reduced portion outside of the bars 4. In the form shown, the rods 11 consist of two tubular portions one adapted to slide in the other, the inner portion being provided at a suitable distance from its inner end with a stop 11^a adapted to extend through and slide in a slot 11^b in the outer portion extending to a sufficient distance from the inner end so that when extended to their full length the rods 11 will not wobble.

Jointed arms 15 have their free ends 16 suitably mounted on two of the rods 11 on the two sides of the rack at the inner end and lower portion thereof and are provided adjacent to where they are jointed with locking devices 17 adapted to hold them in an extended position. In the form shown the locking device 17 consists of a recess 18 in the upper inner portion of the outer member of the jointed arms 15 adjacent to the joint and a projection 19 on the outer portion of the other member adapted when the arms 15 are extended to rest in the recess 18. Any similar locking device may be used. The arms 15 are provided on their inner sides adjacent to the joint with handles 20 for the more convenient manipulation of the arms 15. The arms 15 when extended press the rack outward and upward and hold it in an extended position.

A modified form of attachment of the rack to the sides of the window frame 3 is shown in Figs. 6 and 7. In this form a recess 21 adapted to permit the supporting members 1 to slide therein is provided. In the form shown the recess 21 is formed of any suitable material preferably sheet metal the sides of which are bent outward at right angles to the body and then at right angles toward each other leaving a sufficient space between the inner edges for the passage of the outer portion of the supporting members 1. The recess 21 may be secured to the sides of the window frame 3 in any suitable manner as by screws 22. When this form of

attachment of the supporting members to the window frame 3 is used the sides of the supporting members 1 have rabbets 21^a formed on their outer faces to permit the inwardly inclined portions of the outer faces 70 of the recesses 21 to overlap.

A further modified form of attaching the supporting members 1 to the sides of the window frame 3 is shown in Figs. 8, 11 and 12. In this form the supporting members 1 are pivotally mounted on the sides of the window frame 3. In the form shown, buttons 22 are secured on the outer sides of the supporting members 1 at a distance from their lower ends sufficient to permit the rack when folded to lie beneath the supporting members 1 when turned down. Recesses 23 are provided in the sides of the window frame 3. Plates 23^a provided with openings 25 to permit the insertion of the heads of the buttons 22 and slots 26 extending downwardly and rearwardly from the holes 25 to permit the passage of the shanks of the buttons 22 are secured over the openings of the recesses 23 by any suitable means 90 as by screws 24. Suitable devices 27 are provided to hold the supporting members 1 in a vertical position when it is desired to use the rack. In the form shown, rings or loops 28 are hinged to the sides of the window frame 3 and adapted to pass over the upper ends of the supporting members 1.

If desired a suitable receptacle 29 may be provided to receive and protect the rack when closed and not in use. Such receptacle 100 29 may consist of a body 30 provided with a suitable hinged top 31. The top 31 consists of two portions, a frame 31^a and a removable portion 31^b. The frame 31^a consists of pieces of angle iron 32 secured together at 105 their ends in any suitable manner as by rivets 33 with the open angles inward and upward. The frame 31^a is provided in the vertical flanges at its sides at a distance from the rear edge with pivots 34 having 110 inner portions extending inside of the vertical flanges for a purpose to be later described, the pivots 34 are adapted to pass through apertures 35 in the sides of the body 30 and enter recesses 36 in the window frame 113 3. The frame 31^a is also provided in the vertical flange forming its front edge with apertures 37 adapted to receive hooks 38 movably secured to the sides of the window frame 3, when the frame 31^a is raised to a 12 vertical position. The removable portion 31^b is composed of any suitable material and is adapted to rest in the frame 31 on the inwardly projecting horizontal flanges of the angle irons 32 and to be secured in the frame 31^a by any suitable means, as by spring clamps 39 adapted to be sprung over the inner portion of the pivots 34. When such receptacle 29 is used, the supporting members 1 are suitably secured to the under 125

side of the top 31 as by rivets 40 to the under side of the horizontal flanges of the side angle irons 32 of the frame 31^a.

I claim:—

- 5 1. An extensible clothes rack comprising supporting members adapted to be secured to the sides of a window frame near the bottom thereof, parallel bars on both sides, the inner outer bar on each side secured at an angle to the corresponding supporting member, telescopic rods extending across the window and pivotally connecting the parallel bars at their extremities and centers, and jointed arms provided with locking devices and adapted to extend the rack and hold it in an extended position.
- 10 2. An extensible clothes rack comprising supporting members adapted to be pivotally

secured to the sides of a window frame near the bottom thereof, locking devices mounted 20 on the sides of the window frame and adapted to maintain the supporting members in a vertical position, sides of the lazy tong type the innermost member of the links on each side of the lazy tongs adapted to be secured 25 at an angle to the corresponding supporting member, telescopic rods forming the pivots of the lazy tongs and adapted to extend across the window and jointed arms adapted to extend the rack and hold it extended 30 and provided with locking devices to hold them extended.

JANE KILLIAN McAFFEE.
